KARL KÜPFMÜLLER, OF BERLIN-SCHONEBERG, GERMANY, ASSIGNOR TO SIEMENS & HALSKE AKTIENGESELLSCHAFT, OF SIEMENSSTADT, NEAR BERLIN, GERMANY, A COMPANY OF GERMANY.

PUFIN-LOADED LONG-DISTANCE CABLE WITH PHANTOM FORMATION.

Application filed November 19, 1927, Serial No. 234,452, and in Germany February 3, 1927.

This invention relates to electrical current transmission and particularly to the transmission of signaling currents through circuits formed into a cable.

5 In loaded telephone cables quads of multiple twin formation, in which the two wires of each pair are twisted together and then the pairs twisted into a quad, have been used almost exclusively. In such a cable the capacity in the phantom circuits C_2 is related approximately to the capacity in the pairs C_1 as

$$\frac{C_2}{C_1} = 1.6 \text{ to } 1.7$$

15 Thus, there is a definite relation between the properties of the side circuits and those of the phantom circuits. If, for instance, the cut-off frequency of the side circuits and the attenuation of the side circuits and phantom circuits are fixed, then, of course, the cut-off frequency for the phantom circuits has a definite value.

If the ratio $\frac{C_2}{C_1}$ were to equal 2 and the same 25 attenuation maintained in the side and phantom circuits, then the phantom and side circuits will have approximately the same cut-off frequency. With the ratio of $\frac{C_2}{C_1}$ equal 30 to 1.6 to 1.7 as in the multiple twin quad, a higher cut-off frequency exists for the phantom circuits than for the side circuits, the attenuation in the side and phantom circuits being the same. In this instance the 35 phantom circuit is the better circuit since it is known that the higher cut-off frequency improves the transmission properties of telephone circuits.

40 In the case of the so-called spiral quadded cables in which the four wires of the quad are placed approximately at the corners of a square, the following approximation holds good between the capacity in the phantom and side circuits:

$$\frac{C_2}{C_1} = 2.7 \text{ to } 2.8$$

If in this case the attenuation in the phantom and side circuits are equal, and the cut-off frequency of the side circuits so chosen that it is sufficient for the distances which are to be spanned, then the phantom circuit

will have a cut-off frequency which is too low and the phantom circuit will be practically unserviceable for telephony. As a matter of fact it has been customary to construct spiral quadded telephone cable with the phantom circuits not loaded at all, the phantom circuits having been used, if at all, for subordinate purposes only, such as telegraphy.

An object of this invention is to utilize the various circuits of the different quads contained in a single cable so that each circuit and type of quad is used most economically and efficiently in accordance with the varying number of circuits and circuit lengths. Since the phantom circuit of one type of quad is serviceable over a longer distance than the side circuits of the same type, and vice versa, for the other type of quad above mentioned, this invention relates to the arrangement and use of the circuits of a cable according to these relations. Other types of quads and single pairs may also be contained in the cable.

In describing the invention reference will be made to the drawings in which Fig. 1 shows qualitatively the relationship between the cut-off frequency and the capacity ratios.

80 Fig. 2 shows the relationship between the number of circuits and their lengths.

Fig. 3 illustrates the comparison between the effect of the various degrees of loading for a given geographical spacing of loading points.

85 Fig. 4 shows a multiple twin quad; and Fig. 5 shows a spiraled quad.

In Fig. 1 the graphical relation between the cut-off frequency for the phantom circuits and the ratio of the capacities between phantom and side circuits is shown for a given cut-off frequency for the side circuits. The curve A—B is based on the numerical ratios of the capacities in the multiple twin and spiraled quads when the attenuation is the same in all circuits. The line C represents a definite cut-off frequency for the side circuits which is the same as that for the phantom circuits when the capacity ratio of $\frac{C_2}{C_1}$ is

100 equal to 2. When this ratio is 1.7 as for multiple twin quads, and the cut-off frequency of the side circuits is the same as above mentioned and shown by the line C, then the cut-off frequency for the phantom

circuits is increased to the point A on the curve, making the last mentioned circuits suitable for longer circuits. In the case of the spiraled quads the phantom circuit cut-off frequency is reduced to the point B on the curve because of its 2.7 capacity ratio, these circuits being suitable only for distances much shorter than those for which the side circuits may be used. The curve shows qualitatively how the phantom circuit cut-off frequency varies when the capacity ratio goes from 1.7 to 2.7.

The curve in Fig. 2 represents how the number of circuits for a given traffic problem varies with the length of the circuits. Let us assume that the transmission lengths lie between 150 and 5,000 km., and that the number of required circuits of any particular length is in accordance with this curve, then the area under the curve represents the total number of lines between 150 and 5,000 km. It is seen that the greater number occurs at a length of about 500 km.

It is well known that with increasing length of circuit, the cut-off frequency of the line must also be increased if the same satisfactory transmission is to be maintained. It is also well known that for the same transmission level the cost per unit length of line increases with the increase in cut-off frequency. Now, although it is preferable from a theoretical standpoint to have a different cut-off frequency for each length of circuit, in practice it becomes advantageous to limit the number of cut-off frequencies to a rather small number.

If we assume that a cut-off frequency of about 2,600 cycles per second is suitable for a 400 km. circuit, and that the side circuits of the multiple twin quads have this cut-off frequency, then the phantom circuits of this type of quad may have a range of 800 km. However, as shown in Fig. 2 about twice as many lines are needed in the range of lengths from 400 to 800 km. as in the range from 150 to 400 km., while only half as many phantom circuits as side circuits are available with a definite number of quads. It is obvious, therefore, that the number of phantom circuits serving the number of circuits between 400 to 800 km. is not nearly adequate. The phantom circuits may be exhausted by the circuits having a length of from 400 to 500 km. and for distances above 500 km. a new type of line must be inserted. However, the use of multiple twin quads for distances over 500 km. is favored since the number of circuits decreases as the distance increases.

In order to provide a cable in which the various types of circuits are used to the best economical advantage, both spiraled and multiple twin quads are combined in one cable and the side and phantom circuits of both types of quads are loaded. The lines may be loaded in any well known manner

with either double coils or with combined coil systems.

Referring to Fig. 3 the attenuation in the circuits is plotted against frequency for heavy, medium and extra light loaded circuits and for circuits not loaded at all based on a given geographical spacing of loading points. For purposes of illustration cut-off frequencies of 2,600, 3,600 and 5,000 cycles per second have been given for the heavy, medium and extra light loaded circuits, respectively. From these curves it is seen that the cut-off frequency occurs at lower frequencies for the heavier loaded circuits than for lighter loaded ones although the loss over the usable frequency range increases as the loading becomes lighter. For the shorter systems, therefore, the heavier loaded lines are more practical while the lighter loaded lines are necessary for the longer circuits.

In this invention it is desirable to so load the types of quads that for the shorter length circuits spiraled quads are available, while for the longer lengths multiple twin quads may be used. If it is not desired to be limited to these two types of circuits, still other types may be added for intermediate distances and it may be desirable according to certain circumstances to use either only spiraled or multiple twin quads or again a mixture of quads according to both types. In each case the ratio of mixing the spiraled and multiple twin quads and the method of loading the whole cable is so chosen that the number of lines present for the various ranges is sufficient to meet the actual traffic requirements.

The advantage of a cable made according to this invention will now be explained by way of an actual example assuming that again the number of circuits to be provided is in accordance with the curve shown in Fig. 2.

Previously, the case discussed was where there were multiple twin quads whose side circuits were sufficient for connections of a length up to 400 km. and whose phantom circuits had a range up to 800 km., but were only sufficient to meet the requirements of the number of circuits below 500 km. in range. A more practical distribution is obtained when, according to the invention, spiraled quads are used for the shorter distances, the phantom circuits being so loaded that they have a range of 400 km. Serving over a short distance these circuits may be very heavily loaded. Now, if the side circuits in these quads have the same attenuation as the phantom circuits, they will have a higher cut-off frequency and a range of about two and a half times as long, say about 1,000 km. In this case, however, the number of side circuits is twice as great as the number of phantom circuits and they are sufficient to meet the circuit requirements up to about 750 km. Now, according to the invention, multiple twin quads are provided for the greater

ranges and if the range of the phantom circuits is to be 5,000 km. it would be possible to count on a range of 2,500 km. for the side circuits. These side and phantom circuits are 5 only lightly loaded since they are long distance circuits. The number of side circuits will now suffice to meet the requirements for connections from about 1,600 to 2,500 km. For the mean range of 750 to 1,600 km. a 10 third type of conductor may be used. If spiraled quads are used, however, and the phantom circuits are so loaded that their range is about 900 km. and their number is sufficient for connections between 750 to 900 km., then 15 the number of side circuits which is twice as great is sufficient for connections from 900 to 1,600 km.

As the ranges of the variously stranded and variously loaded cables overlap each other, it 20 is possible to suit the various operating conditions within substantially wide limits.

What is claimed is:

1. In a telephone cable, spiraled quads forming phantom and side circuits, and multiple twin quads forming phantom and side circuits, said side circuits and said phantom circuits being loaded.
2. In a communication cable, spiraled quads forming phantom and side circuits and multiple twin quads forming phantom and side circuits, said phantom circuits of said multiple twin quads being lightly loaded and said phantom circuits of said spiraled quads being heavily loaded.
3. In a communication cable, spiraled quads forming phantom and side circuits and multiple twin quads forming phantom and side circuits, said multiple twin quad circuits being lightly loaded and used for the longer 40 distances while the spiraled quad circuits are

heavily loaded and used for the shorter distances.

4. In a communication cable, spiraled quads forming phantom and side circuits and multiple twin quads forming phantom and side circuits, a certain number of said side circuits of said multiple twin quads being 45 lightly loaded, and a certain number of said phantom circuits of said spiraled quads being heavily loaded.

5. In a loaded cable, spiraled quads forming phantom and side circuits, multiple twin quads forming phantom and side circuits and pairs of single circuits, said spiraled quads being used for the shorter distances and heavily loaded, said multiple twin quads being 50 used for the greater distances and lightly loaded, while said pairs are used for intermediate distances.

6. A method of utilizing a communication cable having a plurality of multiple twin quads of phantom and side circuits and having a plurality of spiraled quads of phantom and side circuits comprising, first, using said phantom circuits of said spiraled quads for 60 the shortest circuits of said cable, second, using said side circuits of said spiraled quads for the next length circuits, third, using said side circuits of said multiple twin quads for 65 the third length circuits, and fourth, using said phantom circuits of said multiple twin quads for the longest circuits.

7. A method of utilizing a communication cable in accordance with claim 6 in which the multiple twin quad circuits are lightly loaded 70 and the spiraled quad circuits are heavily loaded.

In witness whereof, I hereunto subscribe my name this 20 day of October A. D., 1927.

KARL KÜPFMÜLLER.
